SAFETY APPLIANCE FOR PAINTERS AND
THE LIKE

Ed L. Sorensen, Mare Island, Calif.

Application March 16, 1938, Serial No. 196,148

1 Claim. (Cl. 304—16)

(Granted under the act of March 3, 1883, as
amended April 30, 1928; 370 O. G. 757)

The present invention relates to safety appliances for painters and the like and it has a particular relation to a device for securing and slackening off the supporting line of a boatswain's chair or stage.

One of the objects of the present invention is the provision of a device for connecting the supporting line with a boatswain's chair or stage having means thereon for securing the line against movement and for snubbing the line when it is slackened off, the device being so located as to be accessible by the painter in the boatswain's chair.

With this and other objects in view, as well as other advantages that may be incident to the use of the improvements, the invention consists in the parts and combinations thereof herein-after set forth and claimed, with the understanding that the several necessary elements constituting the same may be varied in proportion and arrangement without departing from the nature and scope of the invention, as defined in the appended claim.

The single figure of the accompanying drawing is a side elevational view of safety device and boatswain's chair, the supporting line being in a position to be slackened off.

Referring to the drawing, a safety device constructed in accordance with the invention is shown as comprising a vertical member or shank 10 which is preferably formed from a bar the ends of which are bent upon themselves and toward one another to form upper and lower primary hooks 11 and 12, the former being adapted to be connected with one end of a supporting girtline 13 and the latter being adapted to be connected with a sling or bridle 14 of a boatswain's chair 15. The extremities of the hooks 11 and 12 are again bent upon themselves and away from one another to form spaced upper and lower secondary hooks 16 and 17 around which the free end of the girtline 13 is adapted to be looped and secured by a half hitch in order to maintain the boatswain's chair in the desired

working position. When it is desired to lower the boatswain's chair the half hitch is released and the line held in the position shown in the drawing to permit an operator on the chair to slack away on the line with a snubbing action. 5 The painter or other workman on the chair is thus enabled to control his descent himself as work progresses downwardly without the assistance of a helper below.

It will be observed upon reference to the drawing that the oppositely disposed secondary hooks 16 and 17 are offset with respect to each other in order that the loops of the girtline will not unduly bind upon each other and interfere with the operation of slackening off.

While the safety hook has been shown and described as being formed from a bar, it will be readily apparent that the member 10 may be in the form of a straight bar having eyes provided at its upper and lower ends and with a cleat or 20 the like provided thereon for engagement by the free end of the line.

Other modifications and changes in the construction and arrangement of the parts may be made by those skilled in the art without departing from the nature and scope of the invention as defined in the appended claim.

The invention herein described and claimed may be used and/or manufactured by or for the Government of the United States of America for 30 governmental purposes without the payment of any royalties thereon or therefor.

I claim:

Safety appliance for painters and the like comprising a member having a pair of opposed hooks 35 for connecting a supporting line with a boatswain's chair or stage, and oppositely extending hooks on said first mentioned hooks and disposed in offset relation relative to one another thereon around which the free end of the line is adapted 40 to be looped to secure the same against movement and for snubbing the line when it is slackened away.

ED L. SORENSEN.
